UNITED STATES PATENT OFFICE.

GUSTAF IVAR BARCLAY, OF DETROIT, MICHIGAN, ASSIGNOR TO DETROIT STEEL PRODUCTS COMPANY, OF DETROIT, MICHIGAN, A CORPORATION OF MICHIGAN.

WINDOW.

Application filed January 3, 1927. Serial No. 158,744.

The invention relates to windows and has particular reference to screens attachable to window frames in which are mounted reversible ventilators. Some of the objects of the invention are to provide a simple construction of screen which may be cheaply manufactured; to provide a simple construction of means for detachably securing the screen to the window frame; and to provide supporting means for the screen operating to automatically force the screen laterally toward the frame. With these as well as other objects in view the invention resides in the novel features of construction and combinations and arrangements of parts as more fully hereinafter set forth.

In the drawings:

Figure 1 is an outside elevation of a window embodying my invention; Figures 2, 3 and 4 are cross sections on the lines 2-2, 3-3 and 4-4, respectively, of Figure 1.

The window shown in the present instance has the inwardly opening reversible ventilator 1 and the frame 2. The frame comprises the sill bar 3, lintel bar 4 and the jamb bars 5, and also the weathering strips 6 secured to the jamb bars and the weathering strip 7 secured to the lintel bar. These weathering strips have the inner portions 8 which form channels and the side bars of the ventilator 1 are pivotally connected to suitable shoes sliding in the channels of the jamb weathering strips. The side bars of the ventilator are also pivotally connected at points above the shoes to the lower ends of levers, the upper ends of which are pivotally connected to the jambs and jamb weathering strips near their upper ends. The weathering strips have the transverse flanges 9 which extend into the window opening and overlap the ventilator when closed. These weathering strips also have the intermediate portions 10 connecting the channel forming portions 7 and the transverse flanges 9 and cooperating with the bars of the window frame to which they are secured to form outwardly opening spaces 11. The lintel weathering strip extends over the spaces formed in the frame jambs and its transverse flange 9 forms at the upper ends of the recesses downwardly opening pockets.

12 is the screen comprising the solid metal frame 13 and the screen mesh 14 secured to the outer side of the frame as by solder. The

bottom bar 15 of the screen frame is spaced below the bottom bar of the ventilator when closed and the screen being on the outer side of the screen frame, sufficient clearance is provided for freely moving the ventilator to its desired positions. To detachably secure the screen frame in place and at the same time close the joint between the screen frame and the window frame so that flies, etc., cannot enter, I have provided at the upper ends of the outwardly opening recesses 11 the clips 16 which have bodies 17 extending within the downwardly opening pockets and secured to the transverse flanges 9 of the lintel weathering strips. Each of these clips also has the transverse outwardly extending projection 18 at its lower end which terminates in the transverse flange 19, the projection 18 extending along the edge of a side bar of the screen frame and the flange extending along the outer side of this side bar. 20 is a suitable set screw threadedly engaging the flange and adapted to abut the adjacent side bar of the screen frame for forcing the same against the transverse flanges 9 of the window frame. These set screws are adjustable to also take care of varying thicknesses of screen frame. 21 are supports at the lower end of the screen frame having the bodies 22 extending within the lower ends of the recesses 11 and secured to the intermediate portions 10 of the jamb weathering strips. The lower ends of these bodies are located outwardly of their upper ends and extend below the bottom bar of the ventilator as well as the sill bar of the frame and are provided at their lower ends with the transverse heads 23 which have the downwardly and inwardly inclined shoulders 24 for engaging the lower outer corner of the screen frame to automatically laterally force the same toward and against the transverse flanges 9 of the jamb weatherstrips. These inclined shoulders are so arranged that they provide for wear either of the shoulders or the screen frame without allowing the bottom of the screen frame to come into contact with the upper surface 25 of the heads connecting into the lower ends of the shoulders.

To seal the space between the bottom bar 15 of the screen frame and the sill bar 3 of the window frame, I have provided the flexible closure member 26 which is suitably secured to the lower bar of the screen frame and resiliently engages the outer edge of the

sill bar. This flexible closure permits closing of the ventilator, at which time the bottom bar of the ventilator clamps the closure member against the sill bar of the window frame and thereby holds the screen from unauthorized removal from the outside.

With this construction, it will be seen that the screen frame may be cheaply manufactured and that it may be easily and cheaply 10 detachably secured to the window frame. It will also be seen that when attached to the window frame it is held toward the same to close the joints sufficiently to prevent flies or the like entering.

15 5. What I claim as my invention is:

1. A screen attachable to a window having a frame, and means for detachably securing said screen to the frame, including means adjustably engageable with one end of said 20 screen to laterally force the same toward the frame, and means engageable with the other end of said screen for automatically forcing said screen laterally toward the frame.

2. A screen attachable to a window having 25 a frame formed with outwardly opening recesses at its sides, and means for detachably securing said screen to the frame, including retaining means engageable with the upper end of said screen and extending 30 into the recesses, and supporting means engageable with the lower end of said screen and extending into the recesses, said supporting means automatically forcing said screen laterally toward the frame.

35 3. A screen attachable to a window having a frame, and means for detachably securing

said screen to the frame, including clips secured to the frame having means engageable with said screen for holding the same against the frame, and supporting members secured 40 to the frame and having downwardly and inwardly inclined shoulders engageable with said screen for automatically forcing the same laterally toward the frame.

4. A screen attachable to a window frame 45 having outwardly opening recesses at its sides and having its bottom bar and its screen mesh, respectively, spaced below and laterally outward from the bottom bar of said ventilator, retaining members engageable in 50 the upper portions of the recesses and secured to the frame, and members adjustably engaging said retaining members and engageable with the upper portion of said screen for laterally forcing the same toward 55 the frame, supporting members in the lower portions of the recesses and provided with heads at their lower ends and below the bottom bar of said ventilator, said heads having downwardly and inwardly inclined shoulders engageable with the lower end of said screen for forcing the same laterally toward the frame.

5. A screen attachable to a window having a frame, means for detachably securing the 65 upper portion of said screen to the frame, and a support for the lower end of said screen having means for automatically forcing the same laterally toward the frame.

In testimony whereof I affix my signature.

GUSTAF IVAR BARCLAY.
